FIG. 1

FIG. 2

FIG. 3

FIG. 4

FIG. 5

FIG. 1 is a perspective view of a polygonal bracket for rotatable mounting on a post and for supporting a plurality of radial arms showing my new design.

FIG. 2 is a top plan view thereof.

FIG. 3 is a side view thereof.

FIG. 4 is a bottom view thereof.

FIG. 5 is a section of FIG. 4 taken along line 5-5.

The broken lines in FIG. 1, representing a fragment of a post rotatably supporting said bracket and a plurality of radial arms supported by said bracket, are shown for illustrative purposes only.

I claim:

The ornamental design for a polygonal bracket for rotatable mounting on a post and for supporting a plurality of radial arms, as shown and described.
